UNITED STATES PATENT OFFICE.

WILLIAM F. MARSHALL, OF NORTH ATTLEBORO, MASSACHUSETTS, ASSIGNOR
TO JAMES E. BLAKE COMPANY, A CORPORATION OF RHODE ISLAND.

DESIGN FOR A BACK FOR BRUSHES OR SIMILAR ARTICLES.

SPECIFICATION forming part of Design No. 36,137, dated November 11, 1902.

Application filed September 24, 1902. Serial No. 124,717. Term of patent 3½ years.

To all whom it may concern:

Be it known that I, WILLIAM F. MARSHALL, a citizen of the United States, residing at North Attleboro, in the county of Bristol and State of Massachusetts, have invented and produced a certain new, original, and ornamental Design for the Back of a Brush or Similar Article, of which the following is a specification.

As illustrated, the leading or material features of my design are the representations of various marine subjects arranged in detail as follows: The representation of the head of a single dragon a ornaments the top and one upper side of the back, the representation of a female b and child partially submerged in waves c forms the escutcheon, while the base bears the representation of a single dolphin's head d, from which depends a floral cluster e. Upon the right and left of the escutcheon from the dragon to the dolphin's head are masses of intermingled scrolls and foliates f, including upon one side, adjacent the dragon's head, a water-flower g, upon the opposite side, below the dragon, a second water-flower h.

The handle bears the representation of a human face i, framed in a mass of flowing hair. Beneath the face is a water-flower j and above the former a cluster of foliates k, intermediate which and the floral cluster e are two converging series l of intermingled scrolls, leaflets, and buds.

Having thus described my invention, what I claim as new, and desire to secure by Letters Patent, is—

The ornamental design for the back of a brush or similar article, as herein shown and described.

In testimony whereof I have affixed my signature in presence of two witnesses.

WILLIAM F. MARSHALL.
